UNITED STATES PATENT OFFICE.

LOUIS RUPERT, OF DECATUR, ILLINOIS.

DOOR-KEY FASTENER.

Application filed December 31, 1923. Serial No. 683,702.

To all whom it may concern:

Be it known that I, LOUIS RUPERT, a citizen of the United States, residing at Decatur, in the county of Macon and State of Illinois, have invented certain new and useful Improvements in Door-Key Fasteners, of which the following is a specification.

This invention relates to door key fasteners, and has for its primary object the provision in the manner as hereinafter set forth, of a fastener attached to the escutcheon plate of the door, in such a manner and so constructed as to be always in engagement with the key when it is left in the key-hole of the door to prevent the removal of the key by any person at the other side of the door.

A further object of this invention is the provision in a manner as hereinafter set forth, of a door key fastener having in its structure, means which will automatically cause the fastener to move to engaging position when released.

A final object of the invention is the provision in the manner as hereinafter set forth, of a door key fastener not complicated in structure, easily applied to a door, light, strong, durable and inexpensive to manufacture.

The invention will be best understood from a consideration of the following detailed description taken in connection with the accompanying drawings forming part of this specification, with the understanding that the invention is not confined to any strict conformity with the showing of the drawings, but may be changed and modified so long as such changes and modifications mark no material departure from the salient features of the invention as expressed in the appended claims.

In the drawings:

Figure 1 is a perspective view of that portion of a door wherein the lock is located, showing the device embodying this invention as applied.

Fig. 2 is a vertical transverse view of the device embodying this invention, and of the door and surrounding parts thereof.

Fig. 3 is a detail view of the key engaging plate member which is slidably secured to the plate of the door.

Referring now to the drawings in detail, wherein like numerals of reference indicate corresponding parts throughout the several

views of the drawings, a portion of a door is indicated at 1, showing a conventional form of mortise lock 2 and escutcheon plate 3 having a key-hole formed therein, as at 4, and having the knob 5 extending therefrom, the plate 3, here indicated, taken as being positioned on the inner side of the door 1.

The device embodying this invention comprises a vertically positioned substantially rectangular plate 6 having its lower end turned outwardly at right angles as at 7, forming the finger hold for the actuation of the plate. This plate has its back positioned flat against the face of the escutcheon plate 3 and is adapted to be shifted vertically over the face of this plate and to provide for the retention of the shiftable plate against the escutcheon plate there is provided a stud 8 having one end constricted as at 9 and passed through an aperture in the escutcheon plate 3 at a predetermined distance directly below the key-hole 4, and the inner end of this constricted portion is then swaged over as at 10 to permanently fix this stud in position. The shiftable plate 6 has formed therethrough a vertical longitudinal slot 11 extending from a point adjacent the outstanding tongue 7 at the lower end of the plate to about midway the ends of the plate. Through this slot 11, the stud 8 projects, and after the plate 6 has been placed in position with the stud extending through the slot, a pin 12 is fastened through an aperture previously formed in the stud, and this pin 12 is retained in a position transversely of the plate 6 to prevent the removal of the plate from the stud 8.

A second stud 13 is secured to the escutcheon plate 3 to one side of and slightly below the key-hole 4 and this stud 13 also has its inner end constricted and passed through an aperture in the plate 3 and swaged over as at 14 to permanently retain it in position. An aperture 15 is formed through this stud and near the outer end thereof. This stud 13 is adapted to extend through a second elongated slot 16 formed in the body of the shiftable plate 6, and this slot 16 is positioned adjacent one edge of the plate 6 and in the upper portion thereof. Upon the shifting of the plate 6, the stud 13 also serves to guide the plate and retain the plate in position as does the stud 8, but this stud 13 has a further function, which is as follows.

After the plate is fixed in position and both studs 8 and 13 are extended through their respective slots and the pin 12 is in position, a washer 17 is slipped over the stud 13, and then one end of a helical spring 18 is passed through the aperture 15, and the other end of the spring is extended downwardly and passed through an aperture 19 in the outwardly projected lower end of the plate 6. It will thus be seen that when the plate 6 is drawn down the spring 18 will be expanded and, upon release of the plate 6, the contraction of the spring will draw the plate upward into position to engage a key 20 located in the key hole of the door. A small niche 21 is formed in the upper end of the shiftable plate 6 to receive and engage the body of the key 20.

From the foregoing description, it will be seen that a very effective means is provided to prevent any unauthorized person from removing the key from the key-hole of the door from the outside. Any person upon the inside of the door desiring to remove the key, grasps the outstanding flange 7 with the fingers and forces the same down carrying down with it the plate 6 until the niche 21 is below the lower portion of the key hole 4 whereupon the key may be withdrawn and upon the release of the finger hold 7, the spring 18 which has been expanded during the downward movement of the plate 6 will contract, pulling the finger hold 7 from the stud 13 which is stationary, and automatically drawing the plate 6 upwardly to cover the key-hole, or if the action is reversed and the key has been inserted when the plate was drawn down, the spring would draw the plate back until the niche 21 engaged the body of the key 20, thus covering all of the key-hole below the body of the key and preventing the withdrawal of the key from the key-hole again except by the shifting of the plate which can only be accomplished from the inside of the door.

What I claim is:—

1. The combination with a door having

a key operated lock and including an escutcheon, of a door key fastener comprising a shiftable angle-shaped key retaining member having a pair of elongated vertically positioned slots therethrough, a pair of guide and retaining studs for said angled member secured to said escutcheon and each extending through one of said slots, and a resilient member connecting one of said studs to said angle-shaped member to automatically shift the latter to key retaining position.

2. The combination with a door having a key operated lock and including an escutcheon, of a door key fastener comprising a shiftable angle-shaped key retaining member having a pair of elongated vertically positioned slots therethrough, a pair of guide and retaining studs for said angled member secured to said escutcheon and each extending through one of said slots, a resilient member connecting one of said studs to said angle-shaped member to automatically shift the latter to key retaining position, and removable means carried by each of said studs for removably retaining the said shiftable angle-shaped member in position.

3. The combination with a door having a key operated lock and including an escutcheon, of a door key fastener comprising a shiftable angle-shaped key retaining member having a pair of elongated vertically positioned slots of substantially equal lengths therethrough, the greater portion of one of said slots extending above the other, a pair of guide and retaining studs for said angled member, secured to said escutcheon and each extending through one of said slots, and a spring having one end connected to that stud extending through the upper of the two parts and connected at its other end to said angle-shaped member to automatically shift the latter to key retaining position.

In testimony whereof, I affix my signature hereto.

LOUIS RUPERT.
